(57) **CLAIM**

The ornamental design for a disk shaped LED light housing, substantially as shown and described.

DESCRIPTION

FIG. 1 is a bottom perspective view of an embodiment of the new design;

FIG. 2 is a top perspective view of the embodiment;

FIG. 3 is a top view of the embodiment;

FIG. 4 is a bottom view of the embodiment;

FIG. 5 is a front side view of the embodiment;

FIG. 6 is a left side view of the embodiment;

FIG. 7 is a rear side view of the embodiment; and,

FIG. 8 is a cross-sectional view of the embodiment taken along line 8-8 of FIG. 3.

The design consists of the features of shape, ornament and configuration of the article shown in the drawings. The broken lines shown in the drawings are for the purposes of illustrating portions of the article that form no part of the claimed design. The right side view is a mirror image of the left side view and is therefore omitted. The cross-sectional view is included to further illustrate certain interior portions of the embodiment visible through openings in the outer surface.
